UNITED STATES PATENT OFFICE.

JOHN F. SCHREIBER, OF MILWAUKEE, WISCONSIN.

TIMING-SWITCH FOR AUTO LIGHTING-CIRCUIT.

1,385,954.

Specification of Letters Patent. Patented July 26, 1921.

Application filed July 10, 1919. Serial No. 309,862.

To all whom it may concern:

Be it known that I, JOHN F. SCHREIBER, a citizen of the United States, residing at Milwaukee, county of Milwaukee, and State of Wisconsin, have invented new and useful Improvements in Timing-Switches for Auto Lighting-Circuits, of which the following is a specification.

My invention relates to improvements in 10 timing switches for the lighting systems of motor driven vehicles.

The object of my invention is primarily to provide means whereby the user of a motor driven vehicle may utilize a main 15 switch to connect up his lighting circuits preparatory to leaving the machine, and also whereby he may then utilize another switch to break the lighting circuit, and partially connect up a controlling circuit to be 20 subsequently automatically closed momentarily by an ordinary time piece. This, with minimum expense, may be utilized in connection with an electro-magnet to connect up the main circuit through the lamps at 25 the proper time, and cut out the auxiliary circuit through the time piece and electro-magnet, the time piece being free to perform its ordinary functions as a time piece, and being electrically disconnected at all times, 30 except during the short interval following the closing of the auxiliary circuit, and pending the operation of the electro-magnet in connecting up the main circuit.

In the drawings:—

35 Figure 1 is a fragmentary view in front elevation of a portion of an automobile dash-board or switch plate, to which my invention has been applied, showing the arrangement of the main switch, the time piece and the auxiliary switch with reference to 40 the dash lamp.

Fig. 2 is a plan view of the electro-magnetic mechanism showing conventionally a time piece, one of the lamps, main switch 45 and battery, and also illustrating the circuits, the time piece casing, and electro-magnet casing being shown in section.

Like parts are identified by the same reference characters throughout the several views.

In Fig. 1, the dash lamp 1 and main switch 2 may be assumed to be of any ordinary construction. An ordinary time piece or clock 3 is mounted in a cylindrical casing 4, which is secured to the dash 5. To adapt the clock for my purposes I merely

attach to the hour hand 7 a flexible arm 8, the clock being otherwise unchanged.

But I provide the casing 4 with a cover 4' having a transparent face plate or glass disk 60 9 centrally apertured to receive a metallic button shaped member 11 which performs the function of a binding post, this member being connected with a leading-in conductor 12, and with a terminal arm or electrode 13, 65 having an elbowed extremity 14 in the path of the flexible contact finger 8, carried by the hour hand of the time piece.

Contact finger 8 may be as light and flexible as a hair spring, and in fact I have 70 used a portion of a hair spring very successfully for that purpose. The leading-in conductor 12 is adjusted in pressure contact with a terminal 15 of the auxiliary circuit, which may be connected up in part by an 75 auxiliary push button, and in part by the clock, as follows, to-wit:—from the battery 20 through contact 15, conductor 12, arm 13, elbow 14, flexible contact finger 8, hour hand 7, the clock mechanism, conductor 21, 80 the windings 22 of the electro-magnet, conductors 23 and 24, fixed terminal 25, resilient terminal or switch arm 26, and conductor 27 to battery 20.

The resilient switch arm 26 is held to terminal 25 when push button 16 is moved inwardly, and the push button is locked in such position by a trip latch having an arm 29 which engages a head 30 on the inner end of the push button. The armature 33 of the 90 electro-magnet is provided with an elbowed extension 34, adapted to engage the arm 35 of the trip latch when the magnet is energized, thereby releasing the latch from the push button. The latter is then retracted by 95 the recoil of its spring 36. Therefore, as soon as the magnet is energized by the action of the hour hand of the clock in closing the auxiliary circuit, the resulting movement of the armature 33 releases the push 100 button 16, and allows resilient switch arm 26 to retract and break the circuit through the clock and magnet.

But it will be observed that the switch arm 26 is then included in the main or lighting circuit, for, when retracted, it automatically moves to contact electrode 40 by its own resiliency. This is connected with the main switch 2 by conductor 41. The main circuit is dependent merely upon push button 2 being in circuit closing position, and upon arm 26 being on contact 40.

The terminal arm or electrode 13 is adjustably connected with the member 11, being rotatable about the center of the member 11, and preferably having a disk shaped extremity in contact with the member 11 at all points of adjustment. Therefore, it is obvious that if the arm 13 is adjusted in registry with any given mark upon the dial the auxiliary circuit will be connected up, and the lights turned on when the hour hand reaches that point if the switch 2 has been actuated to connect up the main circuit with the lamps. Therefore, the user will be able to leave his machine at any time during the day, and may rely upon the lights being turned on when darkness approaches, by merely operating his main switch 2 in a manner to turn on the lights, and then pushing button 16 inwardly until the latch arm 29 engages the inner head 30 of the push button, arm 13 being set to indicate the hour or fraction thereof at which the auxiliary circuit will be closed by the contact finger 8. This will be accomplished without material loss of electrical energy in the switch mechanism, for the auxiliary circuit is only closed momentarily, and during this momentary period the lighting circuit will be almost simultaneously closed. The current which passes through the clock mechanism will do no damage, although it is, of course, possible to avoid passing the current through any other portion of the clock, except the hour hand, by electrically connecting conductor 21 thereto, independently of the clock casing.

I attach considerable importance to the fact that the adjustable contact arm or terminal 13, and the leading-in conductor 14 with associated parts, are mounted upon the cap or cover 7, which has a transparent disk through which the clock may be viewed, but which forms no part of the clock mechanism, and is not affected by the operation of the clock mechanism, except during the short interval of contact finger 8, and it is only during a portion of this interval that the circuit through the magnet is closed.

The object of merely adjusting the conductor 12 in pressure contact with the electrode 15 as distinguished from other means of connection, is to enable the user to remove the time piece more readily. Ordinarily the time pieces used for these purposes will have winding stems at the rear side.

I claim:

1. A timing switch mechanism for vehicles, including the combination with a lighting circuit and a source of electrical current, of a main switch, an auxiliary manually and automatically operable switch to open and close the lighting circuit, an automatically retracting auxiliary switch, an electro-magnetic trip mechanism for temporarily holding the auxiliary switch in circuit clos-

ing position, and a time piece provided with a movable member, adapted to close a circuit through the electro-magnet at a predetermined time, said auxiliary switch, when retracted, being adapted to connect up the lighting circuit independently of the electro-magnetic mechanism.

2. A timing switch mechanism for a vehicle lighting circuit, including the combination with such lighting circuit and a source of electrical current, of a main switch for making and breaking said circuit, an auxiliary circuit provided with switch mechanism, also controlling the main circuit, an electro-magnet for operating the switch mechanism, and a time piece provided with a circuit closer, upon which the auxiliary circuit depends, said auxiliary switch mechanism being adapted, when the electro-magnet is energized, to automatically break the auxiliary circuit and close the main circuit.

3. A time controlled circuit closing mechanism for lighting circuits, including the combination of a time piece, provided with a circuit closing contact arm, a cover for the time piece provided with an adjustable contact terminal in the path of said arm, and having a transparent portion through which the dial of the time piece may be viewed, a push button electrically connecting said terminal and said mechanism, an electro-magnetic mechanism, said mechanism adapted to electro-magnetically close a lighting circuit when said arm and terminal are in contact.

4. In a timing switch mechanism for lighting circuits, the combination with a time piece provided with a rotary contact arm, a transparent cover for the time piece provided with a rotatively adjustable terminal, having one portion in the path of said arm when said contact arm and terminal are in engagement, and electrically operated mechanism controlled by said contact arm and terminal for connecting up the lighting circuit, said lighting circuit having a shunt which includes said contact arm and terminal, and said electrically operated mechanism.

5. In a timing switch mechanism for lighting circuits, the combination with a time piece provided with a rotary contact arm, a transparent cover for the time piece provided with a rotatively adjustable terminal, having one portion in the path of said arm when said contact arm and terminal are in engagement, and electrically operated mechanism controlled by said contact arm and terminal for connecting up the lighting circuit, said lighting circuit having a shunt which includes said contact arm and terminal and said electrically operated mechanism, said electrically operating mechanism being adapted to break the shunt cir-

cuit while connecting up said lighting circuit.

6. A timing switch mechanism, comprising the combination with a main lighting circuit having a manually operable switch, and a shunt circuit, including an electromagnet, of a movable switch arm adapted to alternatively connect up the main circuit in one position and the shunt circuit in another position, a manually adjustable trip adapted to temporarily retain said arm in position for closing said shunt circuit, an armature adapted to be actuated by said electro-magnet to release the trip, and allow said arm to open the shunt circuit, and close said main circuit, and timing mechanism having a movable member adapted to complete the shunt circuit at predetermined periods when said arm is held by the trip in

20 a position to connect up such circuit.

7. A timing lighting system comprising the combination of a main lighting circuit having a manually operable switch for con-

trolling said circuit; a shunt circuit independent of said manually operable switch; an electromagnet in said shunt circuit; a resilient switch arm adapted in one position to alternately complete said main circuit when said manually operable switch is closed, and adapted in another position to partially complete said shunt circuit; a spring pressed plunger adapted to be manually operated to cause said resilient arm to partially complete said shunt circuit; an armature actuated by said electromagnet to release said plunger and allow said resilient arm to open said shunt circuit and complete said main circuit, and timing mechanism for completing said shunt circuit at predetermined times.

In testimony whereof I affix my signature in the presence of two witnesses.

JOHN F. SCHREIBER.
